BASKET MAKING MACHINE

James D. Brooks, St. Petersburg, Fla., assignor
to Steel-Bound Container Corporation, St.
Petersburg, Fla., a corporation of Florida

Application June 26, 1930, Serial No. 464,034

3 Claims. (Cl. 1-12)

This invention relates to a device for forming lengths of fabricated material.

An object of the invention is the provision of a machine for continuously connecting laths, paling, or staves to spaced metal straps in such a manner that no nails or securing means other than the punched pointed lugs formed on the metal straps will be employed, the pointed lugs being forced through the strips of spaced wood and having their ends bent upon the opposite sides of the strips for securing the strips of wood to the metal straps.

Another object of the invention is the provision of a machine for continuously connecting strips of flat wood to metal straps, the metal straps being cut and punched to form lugs which will penetrate the wood with the ends of the lugs being clinched upon the strips of wood securely fastening the piece of wood to the straps, means being employed for cutting the fabricated material in suitable lengths.

A further object of the invention is the provision of a machine for cutting metal straps to form lugs while bending said lugs at right angles to the surface of the straps after which the lugs are forced through spaced strips of wood carried in spaced relation through the machine, the punching and cutting mechanism comprising a pair of revolving wheels having spaced punches and dies radially disposed at the periphery of the wheels.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a side view in elevation of a machine constructed in accordance with the principles of my invention.

Figure 2 is a side view in elevation of the machine showing the system of gearing.

Figure 3 is a plan view.

Figure 4 is a vertical longitudinal section of the machine.

Figure 5 is a section taken along the line 5-5 of Figure 1.

Figure 6 is a section taken along the line 6-6 of Figure 1.

Figure 7 is a transverse vertical section taken along the line 7-7 of Figure 1.

Figure 8 is a section taken along the line 8-8 of Figure 1.

Figure 9 is a horizontal section taken along the line 9-9 of Figure 1.

Figure 10 is a fragmentary side view in elevation of the punching and cutting elements.

Figure 11 is a fragmentary view in perspective of a belt for carrying the strips of wood,

Figure 12 is a view in perspective of an adjusting block,

Figure 13 is a view in perspective of a pair of ends of the metal straps secured together,

Figure 14 is a view in perspective of an element of the cutting and punching die,

Figure 15 is a view in perspective of the other element of the die,

Figure 16 is a view in perspective of a piece of metal strap which has been cut and punched by the co-operating elements shown in Figures 10, 14, and 15, and

Figure 17 is a view in perspective of a block equipped with a cutter and punches.

Referring more particularly to the drawings, 20 designates spaced standards forming side walls of the machine, the side walls being provided with 25 a plurality of bearings 21, 22 and 23 at the upper periphery.

A motor 24 is carried by the standards 20 and is provided with a pulley 25 for driving a belt 26. This belt extends upwardly to the ceiling 30 where it drives a pulley and shaft, not shown. A second belt 27 is driven by a pulley which is driven by the shaft and pulley just described. The belt 27 drives a pulley 28 rigid with a shaft 29.

A shaft 29 drives a gear 30 which in turn drives 35 a gear 31 in mesh with a gear 32 and a gear 33. The gear 33 drives a gear 34 which meshes with a gear 35. These various gears are driven in the direction indicated by the arrows in Figure 2. A gear 36 is driven by the gear 34 and meshes 40 with a gear 37. The last-mentioned gear in turn drives a gear 38 rigid with a shaft 132. The gear 37 is keyed to a shaft 133.

A plurality of wheels are arranged in spaced relation at the forward end of the machine and 45 are arranged to be revolved by the drawing of the metal straps through the machine in a manner which will be presently described.

A wheel, generally designated by the numeral 41 is located adjacent one of the standards 20 while a wheel, generally designated by the numeral 42, is located adjacent the other standard. A third wheel, generally designated by the numeral 43, is located intermediate the wheels 41 and 42.

The wheel 41 consists of a disc 44 provided with a hub portion 45 from which projects radially a boss 46. Mounted in the boss is a pin 47 having a flange 48 engaged by one end of a spring 49. The other end of the spring is engaged by a cap 50 threaded into the outer end of the boss 46. A handle 51 located at the outer end of a stem 52 connected with a pin 47 provides means for precipitating the pin. The inner end 10 of the pin is located within one of two annular grooves 53 formed in a shaft 54 which is carried by a bearing 55 at the upper end of the standard 56. A set screw 57 secures the shaft 54 against rotation in the bearing 55.

15 A second disc 58 is spaced from the disc 44 by means of an offset cup-shaped member 59 formed integrally with the disc 58 and located adjacent the center of the disc. The cup-shaped member has a hub portion 60 received by one end of 20 a stub shaft 61 and a bushing 62 is squeezed into the hub section 60 and located between the shaft 61 and the inner wall of the hub section. The shaft 61 is supported in a bearing 21 formed at the upper edge of the plate 20.

25 The disc 58 is maintained in position by means of a cap 63 which has an inwardly projecting member 64 seated within a complementarily formed recess at the inner end of the shaft 61 and a set screw 65 secures the cap 63 in position so that the portion of the cap adjacent the periphery and at the inner face abuts the bushing 62 and aids in retaining the disc 58 30 in a predetermined plane.

It will be noted that the cup-shaped member 59 being offset with respect to the disc 58 provides an annular shoulder 66 and in connection with the disc 58 and the disc 41 provides an annular chamber or groove to receive the metal straps 67 which are wound upon the wheel 40 or spool 41.

The wheel or spool 43 is formed of a disc 70 having a hub portion 71 carrying a boss 72 in which is slidably mounted a pin 73 with its inner end mounted within a groove 74 formed in the shaft 54 and maintains the disc 70 in a predetermined spaced relation with respect to a disc 75 forming the other element of the spool or wheel 43.

The disc 75 has a cup-shaped member 76 50 formed centrally of the disc 75 and is provided with a hub section 77 in which is forced a bushing 78 to receive one end of a shaft 79. The end of the shaft which is received within the hub section 77 has a cap 80 secured thereto and 55 engages one end of the bushing 78 for maintaining the cup-shaped member in a predetermined spaced relation with respect to the disc 70.

The cup-shaped member 76 has an annular shoulder 81 which, together with the disc 70 60 and the disc 75, provide an annular groove to receive a metal strap 82 which is wound upon the spool 43.

The wheel or spool 42 is identical in construction with the wheel 58 and will not be described 65 in detail. A pin 83 having its inner edge fitted within a groove 84 formed in the end of the shaft 79 maintains a disc 85 forming one element of the spool 42 in a predetermined position. The disc 58 has its upper end spaced from the disc 42 to provide an annular groove to receive a metal strap 86 which is wound upon the spool. The brackets 56 which are located upon opposite sides of the spool 43 are carried by transverse bars 87 mounted upon the standard 20.

75 Referring more particularly to Figures 3, 5, 10,

14 and 15 it will be seen that a unit is incorporated in the machine for cutting the straps and for forcing penetrating lugs in right angular positions with respect to the straps. A shaft 90 is driven in one direction by the gear 34 while the gear 35 drives a shaft 91 in the opposite direction. These shafts are mounted in bearings 92 formed in the standards 20. On the shaft 90 are keyed three discs, respectively, 93, 94 and 95. A ring 96 is secured to one face of the disc 93 while 10 a ring 97 is secured to the opposite face by means of pins 98. These pins likewise secure in radial relation one of the elements 99 of a die. A wheel or disc 100 is carried by the shaft 91 and located in the same vertical plane with the disc 93. This 15 disc also has a ring 101 secured to one face adjacent the periphery while a ring 102 is secured to the opposite face by means of pins 103. An element 104 of the die is formed in a complementary manner to the element 99 and a plurality of elements 104 are supported by the pins 103 around the periphery of the disc 100 and are adapted to be aligned end to end with the elements 99. The disc 105 is located intermediately of the discs 100 and 100^a shown in Fig. 5 and keyed to the shaft 25 91. The disc 105 is formed in a similar manner to the disc 100 except that the rings 106 and 107 aid in retaining a pair of elements 104^a upon opposite faces of the disc 105. The pins 103 retain the elements within pockets formed at the periphery of the disc 105.

The disc 94 is similar to the disc 93 except that it has two circular rows of elements 99^a located at opposite faces of the disc 93 and in co-operation with the elements 104^a cut and force the 35 prongs 108 shown in Fig. 16 upon opposite side edges of a strap 82 in a manner which will be presently explained.

The disc 95 is similar in all respects to the disc 93 and the disc 100^a is similar in construction to 40 the disc 100. The construction of these two discs will not be described in detail.

Referring more particularly to Figures 14 and 15 it will be seen that the two elements of the die are particularly illustrated. The element 104 45 which is applied to the discs 100—105—100^a consists of a body portion 110 which is provided with a passage 111 to receive a pin 103. The body portion is provided with a central groove 112 which is V-shaped in cross section. On the outer end 50 of the body portion is provided an edge 113 intermediate a pair of faces 114—115 inclined away from said edge. The face 114 where it connects with one face of the groove 112 provides a cutting edge 116. The outer end of the body portion is 55 sheared off at an angle, as shown at 117, and a cutting edge 118 is formed at the outer end of the inclined face 117 and the face 114. A second cutting edge 119 is formed between the other face of the groove 112 and an edge of the face 115. A 60 cutting edge 120 is disposed at an angle to the edge 114 and is formed along a line where the inclined edge 117 meets the face 115.

The other element 99 of the die has a body portion 122 which is provided with a passage 123 65 to receive the pin 98. One face of the body is provided with a pair of V-shaped grooves 124 and 125. These grooves are V-shaped in cross section and provide a centrally disposed V-shaped rib 126. The rib 126 together with the grooves 70 124 and 125 in connection with the outer flat face 127 of the body, provide pairs of cutting edges 128 and 129 which co-operate with the cutting edges 118, 116, 119 and 120 to not only cut the straps 82, as shown in Fig. 16 to form the lugs 75.

108, but the inclined faces 114 and 115 force said pointed lugs at right angles to the body of the strap for a purpose which will be presently described. The edges 130 and 131 of the element 5 104 ride within the grooves 124 and 125, respectively, when the respective discs 93—100, 94—105, 95—100^a, are revolved in intermeshing relation, as shown in Figure 5.

The three straps 67, 82 and 86 are drawn 10 through the machine by means of pairs of rollers illustrated more particularly in Figure 8 and are revolved by a pair of shafts 132—133 which are driven respectively by the gears 38 and 37. A pair of spaced wheels 134 are keyed to the shaft 133 15 and may be cast or they may be formed of sections 135, 136 and 137 which are connected together by threaded studs 138. The members 135 and 136 have portions cut away at the periphery to provide annular grooves 139 to receive the lugs 20 108 on the straps 82 and the straps 67 and 86.

Since the intermediate strap has formed thereon lugs 108 upon both of its opposite edges, the wheel 140 located between the wheels 134 is provided with a pair of grooves 145 to receive the 25 pointed lugs. Wheels 146 mesh with the wheels 140 and co-operate with said wheels for gripping the straps and pulling them through the machine and off of their spools. The wheels 147 co-operate with the wheels 134 and grip the outermost 30 straps for pulling said straps through the machine. The wheels 147 are provided with annular ribs 148 which are adapted to be received within the grooves 149 formed in the wheels 134.

Wheels 146 are also provided with annular ribs 35 150 which are received within grooves 151 of the wheels 140.

The shaft 133 is mounted in stationary bearings 152 while the shaft 132 has its ends received within a passage 153 formed in movable bearings 40 154. These bearings are provided with radially disposed grooves 155 which receive beading 156 formed in the ways 157 in which the bearings 154 are mounted. The ways 157 are cut in the standard 20. A spring 153 embraces the stem 159 45 formed integrally with the bearing block 154 and abuts at one end said bearing block while the other end of the spring engages a bar member 160. By releasing the nuts 161 the bearing 154 may be moved outwardly to provide a predetermined degree of spacing between the wheels 134—147 and 140—146 in order to accommodate 50 straps of different thickness. The bar or member 160 is held in position by nuts 161 located upon opposite sides of the stem 159 and the bolts carrying the nuts are mounted on the frame of the 55 machine.

A hopper, shown more particularly in Figures 1, 2, 3 and 4, is provided at the front end of the machine and disposed in a vertical manner to receive flat strips of wood 170. These flat strips 60 may be formed of veneer and they may represent staves of a basket or barrel or they may represent palings and these flat pieces may be formed of composition material instead of wood if desired. The hopper 171 has its lower end open to travelling conveyors 172 which are driven by wheels 173 and through the gears 39 and 31. The wheels 173 are secured to a shaft 174. The travelling conveyors are in the form of hard surfaced 65 belts 175 (Fig. 11) which have secured at the outer end a strap of leather 176 which is adapted to abut an outer end of the strips of material 170 while being carried through the machine. Cleats 177 are secured in spaced relation on the belt 70 75 175 and the strips of wood are adapted to be

received between the said cleats for aiding in maintaining the strips of wood in spaced relation during the travel through the machine. The belts are provided with perforations 178 adapted to receive projections 179 on the wheels 173 (see 5 Fig. 6). It will be noted from Figure 6 that the intermediate wheel 173^a is devoid of the rib 176 which is found on the wheels 173.

A series of wheels 180 are keyed to the shaft 181 and this shaft is driven by the gear 32 while 10 shaft 174 is driven by the gear 31. The wheels 180 are of less width than the rims 182 of the wheels 173 and 173^a and the outer faces of the wheels 180 are adapted to cooperate with the rims 182 and force the lugs 108 of the metal straps 15 passing between the said wheels into the strips of wood 170 as they arrive at intervals and the outer free ends of the lugs are bent over against the outer faces of the pieces of wood so that the strips of wood are rigidly secured to the straps. 20

When it is desired to cut the material formed in the machine in predetermined lengths, it is only necessary to supply the wheels 180 with a knife 190 and for this purpose each of the wheels are cut off at the periphery, as shown at 191, to 25 receive a block 192 which carries a knife. Where continuous lengths of the fabric are intended to be made in the machine, as in the case where rolls of material are formed for use as a fence, the knives are removed. As is clearly evident in Fig. 10, 30 projections 108 will be formed in the metal bands for clinching the wooden slats thereto, and that one series of projections will be spaced from the preceding and succeeding series a distance somewhat greater than the distance between the respective pairs of projections in any series. This is desirable because this greater length of band between series may be used to better advantage for formation of the fastening eyes 197.

Referring more particularly to Figure 13, it will 40 be seen that the ends 195 and 196 of the metal straps 67 are provided with pressed-out eyes 197 to receive a pin 198 for connecting the ends of the straps together in the manufacture of barrels or baskets. For this purpose dies are formed 45 which are shaped in accordance with the pressed-out members 197 in the wheels 180 and complementarily formed depressions are located within the peripheries 182 of the wheels 173 and 173^a. These dies and depressions are formed in the 50 sections 192 in order that the eyes 197 may be formed as the ends 195 are cut from the straps.

A shoe 200 has an arm 201 which is pivotally mounted on a rod 202 which extends transversely of the machine, the rod being carried by the 55 standards 20. A shoe is located adjacent each of the wheels 100—105 and 100^a and acts as a guide for the straps when said straps are leaving the spools 41, 42 and 43. These shoes by their weight exert sufficient pressure upon the straps to aid 60 in maintaining the straps taut.

The operation of my device is as follows: The material in the form of strips 170 are placed within the hopper 171 and the lowermost strip will rest upon the travelling carrier 172. These strips, 65 as has been previously described, may be connected to the straps for the purpose of forming the side wall of a basket or barrel or the strips may be connected to the straps in spaced relation for fencing. Whatever the purpose of the ultimate application of the manufactured article the method of forming the article is identical in each case except that certain changes will be required although not material in order to adapt the machine to the particular product. In other words 70 75 75

in the manufacture of fencing or in the construction of barrels, or palings or staves, must be longer than the members forming the side walls of a basket. In this instance it will be only necessary to utilize a greater number of the forming elements.

As soon as the motor 24 is set in motion the wheels 173 will be revolved, causing the travelling carrier 172 to receive and move the slats or strips 10 of material towards the pair of co-operating wheels 173 and 180. At the same time the drawing wheels 134—147, 140—146, will pull the straps inwardly and since the die wheels are revolving they will cut and form the lugs 108 along one edge 15 of the metal straps 67 and 86 while the die wheels will cut and form the lugs upon opposite edges of the straps 82 which are travelling centrally of the machine. The travelling carrier moves the pieces of wood to the groups of intermeshing wheels 173 20 and 180 and the mechanism is so timed that these strips of wood will arrive at the intervals when the prongs or lugs 108 of the straps will be moving between the wheels so that said lugs will be forced through the strips of wood and have their 25 outer ends which have penetrated the strips of wood swaged over, thereby locking the strips of wood to the straps. It will be appreciated that the hard surface belts 175 in conjunction with the wheels 173 serve to clinch the prongs 108 30 against the exposed face of the wooden slats.

As has been previously explained, cutters 190 may be inserted on the wheels 180 in order to sever pre-determined lengths of the manufactured product for the formation of baskets or 35 barrels. When fencing is manufactured the cutters will be removed and continuous straps of the product are formed.

It will be noted that the die elements 99 and 104 have their outer ends moving towards each 40 other at an angle so that the cutting and the forming of the lugs at right angles to the plane of the straps is gradual.

The block 192 is not only provided with a cutter

190 but with punches 300 located upon opposite sides of the cutter so that when the wheel 180 is revolved and the cutters and punches move into contacting relation with the wheel 173 the straps 82 will not only be cut off but portions of the straps on each side of the cut will be punched to form eyes 197 shown more particularly in Figure 13.

I claim:

1. A machine for assembling bands and slats, comprising means for directing the bands through the machine in substantially parallel relation, and means for forming projections on the bands in longitudinally spaced relation with respect to each other, said means being of such character, that at 15 predetermined intervals the projections are spaced a greater distance than the usual distance between projections.

2. A machine for assembling bands and slats comprising means for directing the bands through 20 the machine in parallel relation, means for stamping spaced projections in the bands for respectively securing wooden slats thereto, means for severing the bands between predetermined lengths, and means for forming fastening eyes in 25 the bands at each side of the line of severance, such means being of such character that the eye at one side of the line of severance is complementary to the eye at the other side when the ends of the bands subsequently are disposed in overlap- 30 ping relation.

3. A machine for assembling bands and slats, comprising means for directing the bands through the machine in substantially parallel relation, means for forming projections on the bands in 35 longitudinally spaced relation with respect to each other, means for automatically spacing the projections at predetermined intervals at greater than the usual distance between projections, and means for forming end fasteners in the bands at such 40 points where the projections are spaced a greater amount.

JAMES D. BROOKS.
